(57) **CLAIM**

(21) Appl. No.: **29/181,401**

The ornamental design for a chromatography column locking ring, as shown and described.

(22) Filed: **May 9, 2003**

DESCRIPTION

(51) LOC (8) Cl. **24-01**

The design is a locking ring that can fit into an opening of an end of a chromatography column assembly.

(52) U.S. Cl. **D24/224**; D10/103

FIG. 1 is a perspective view of a chromatography column locking ring showing my new design;

(58) Field of Search D24/224, 216;

FIG. 2 is a front elevational view thereof;

D10/81, 103; D9/435, 445, 452, 454; 210/198.2,

FIG. 3 is a side elevational view thereof;

656; 422/102, 99, 58

FIG. 4 is a top plan view thereof; and,

D357,200 S * 4/1995 Thomas D10/103

FIG. 5 is a bottom plan view thereof.
